CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND MEANS TO DELAY THE SUCCESSIVE OPENING THEREOF

Application filed May 31, 1929. Serial No. 367,433.

This invention relates to electro-magnetically controlled electric switches and to closing and opening apparatus and circuits therefor.

- 5 It frequently happens that an operative, especially with switches adapted for the control of industrial apparatus, as motors, repeatedly opens and close the switch rapidly when there is no need for it, thereby unnecessarily heating the contact members of the switch and drawing destructive arcs between them and also placing unusual demands upon the circuit of the switch and the apparatus associated therewith.
- 10 13 It is an object of the present invention to provide an electric switch and its control apparatus and circuits with means so arranged that after the switch has once been opened, it can not again be reclosed until the expiration of a predetermined time interval, which interval is adapted to be sufficiently long to permit the contact members to become cool and the hot arc gases to be dissipated.

The switch with which the present invention particularly is concerned is an electro-magnetically operated switch having an electro-magnet that is adapted to be energized to close the switch and to be maintained energized for so long as the switch is to be held closed. The control apparatus for such a switch includes a push button operated circuit controller to insure the initial energization of the electro-magnet and the closing of the switch and a second push button operated circuit controller that is adapted to be operated to break the circuit of the electro-magnet and permit the switch to open. The first or starting circuit controller is normally open and the second or stopping circuit controller is normally closed. Both circuit controllers have appropriate control circuits associated therewith.

It is an object of the present invention to associate electro-responsive means, and particularly thermal relays, with the circuits of both circuit controllers, which means shall be so arranged as to be operated by one circuit to disable the other circuit and prevent rapidly repeated closing operations of the switch and especially to prevent the reclosing of the

switch for a predetermined time interval after it has been opened under load.

A further object of the invention is generally to improve the construction and operation of electric switches and control apparatus and systems therefor.

Fig. 1 is a diagrammatic illustration of the switch and its control apparatus and circuits embodying the present invention.

Fig. 2 is similar to Fig. 1 except that a modified arrangement is provided for preventing rapid reclosing operations of the switch.

Fig. 3 is a modification of Fig. 1 wherein a normally open thermal relay is substituted for the electro-magnetic relay.

The switch with which the present invention is particularly concerned includes a movable bridging member 10 which is adapted to be moved upwardly to engage and bridge the stationary contact members 12 which are included in series with one of the circuit conductors 14 of the herein shown single phase circuit that includes the other conductor 16. The switch may control the supply of power to any power consuming device as the motor 18. While the switch here shown is illustrated as being in but one conductor of the circuit, it is to be understood that the switch can have cooperating contact members arranged in all of the conductors of the circuit as is common practice. The bridging member 10 is mounted on an insulating bar 20 carried by the switch arm 22 which is pivoted loosely at its free end to one leg of an electro-magnet 24 which has an actuating winding 26. The arrangement is such that when said winding is energized, the electro-magnet attracts the lever 22 and moves the bridging member into engagement with the fixed contact member 12, thereby closing the switch. The switch is held closed by maintaining the electro-magnet energized. The circuit of the electro-magnet is controlled by a pair of push button controlled circuit controllers, there being the starting push button 28 which is arranged to initially energize the magnet to effect the closing of the switch and a second or stopping push button 30 which serves to effect the de-

70 75 80 The switch may control the supply of power to any power consuming device as the motor 18. While the switch here shown is illustrated as being in but one conductor of the circuit, it is to be understood that the switch can have cooperating contact members arranged in all of the conductors of the circuit as is common practice. The bridging member 10 is mounted on an insulating bar 20 carried by the switch arm 22 which is pivoted loosely at its free end to one leg of an electro-magnet 24 which has an actuating winding 26. The arrangement is such that when said winding is energized, the electro-magnet attracts the lever 22 and moves the bridging member into engagement with the fixed contact member 12, thereby closing the switch. The switch is held closed by maintaining the electro-magnet energized. The circuit of the electro-magnet is controlled by a pair of push button controlled circuit controllers, there being the starting push button 28 which is arranged to initially energize the magnet to effect the closing of the switch and a second or stopping push button 30 which serves to effect the de-

85 90 95 The switch may control the supply of power to any power consuming device as the motor 18. While the switch here shown is illustrated as being in but one conductor of the circuit, it is to be understood that the switch can have cooperating contact members arranged in all of the conductors of the circuit as is common practice. The bridging member 10 is mounted on an insulating bar 20 carried by the switch arm 22 which is pivoted loosely at its free end to one leg of an electro-magnet 24 which has an actuating winding 26. The arrangement is such that when said winding is energized, the electro-magnet attracts the lever 22 and moves the bridging member into engagement with the fixed contact member 12, thereby closing the switch. The switch is held closed by maintaining the electro-magnet energized. The circuit of the electro-magnet is controlled by a pair of push button controlled circuit controllers, there being the starting push button 28 which is arranged to initially energize the magnet to effect the closing of the switch and a second or stopping push button 30 which serves to effect the de-

95 100 The switch may control the supply of power to any power consuming device as the motor 18. While the switch here shown is illustrated as being in but one conductor of the circuit, it is to be understood that the switch can have cooperating contact members arranged in all of the conductors of the circuit as is common practice. The bridging member 10 is mounted on an insulating bar 20 carried by the switch arm 22 which is pivoted loosely at its free end to one leg of an electro-magnet 24 which has an actuating winding 26. The arrangement is such that when said winding is energized, the electro-magnet attracts the lever 22 and moves the bridging member into engagement with the fixed contact member 12, thereby closing the switch. The switch is held closed by maintaining the electro-magnet energized. The circuit of the electro-magnet is controlled by a pair of push button controlled circuit controllers, there being the starting push button 28 which is arranged to initially energize the magnet to effect the closing of the switch and a second or stopping push button 30 which serves to effect the de-

energization of the magnet and the opening of the switch.

The starting push button 28 controls a normally open circuit controller and has spring means 30 supporting the movable contact member 32 which goes in and out of contact with the fixed contact members 36 and 38 of the circuit controller. The push button 28 is adapted to be momentarily depressed to close its circuit controller and, when the pressure is relieved, moves upwardly to open its circuit. The stopping button 30 controls a normally closed circuit controller and has spring means, not shown, which maintains the movable contact member 32 of the controller normally in bridging engagement with the fixed contact members 36 and 38. When said push button 28 is depressed, the circuit controller is opened, resulting the opening of the switch, and when the pressure on the push button is relieved, the circuit controller is closed.

The terminal of the winding 40 of the electro-magnet is connected to a conductor 46 to the conductor 16 of the power circuit. The other terminal of the winding is connected to the conductor 48 with the contact member 44 of the stopping circuit controller, and through the controller with the contact member 38 of the starting circuit controller. The other contact member 36 of the stopping circuit controller is connected to the conductor 46 or the other conductor of the power circuit. The electric starting circuit controller is bypassed, the electro-magnetic winding 40 connected between the switch 10 and the conductor 16, the circuit of the switch 10 being closed to form a silent circuit for the starting motor, and the starting circuit controller or switch 10 can be opened without opening the switch to open. Said switch 10 is connected to a conductor 52 which is connected with both the contact members 36 and 38 of the two controllers. Thus, when the switch 10 is closed, the circuit through the controller 48 is maintained by reason of the closed switch 10, even though the starting circuit controller is opened. When the switch 10 is opened by the operation of the stopping button 30, the switch 10 stays open until the opening of the starting circuit controller.

Protective means are provided against the opening of the switch upon an overload or other abnormal condition in the power circuit. The protective means here shown includes a thermal relay consisting essentially of an electrical resistance heating element 54 and a thermally expansible element 56. The heating element 54 is included in the circuit of the conductor 16 and thereby is heated by current which is proportional to the current in the power circuit. The thermal element 56 is disposed in heat-receiving

relation with said heating element. Said thermal element comprises a metal strip that is composed of two metals having dissimilar coefficients of expansion secured together. Said thermal element controls the engagement and separation of a pair of contact members 58 which are included in the conductor 48 and in series with the stopping circuit controller and the electro-magnet winding. Said contact members are normally in engagement and are adapted to be separated by the expansion and consequent flexing of said thermal element 56 thereby to open the circuit of the electro-magnet and effect the opening of the switch. The arrangement so far described is common in the art with the exception that the electrical isolation between the electric heater element and the thermal element of the relay is described and claimed in a pending application of George W. O'Keefe, Serial No. 364,149, filed May 18, 1933, and assigned to the assignee of the present application.

In accordance with the present invention, means are associated with the above described apparatus and circuits to prevent the rapidly repeated reclosures of the switch under load and specifically to prevent the reclosing of the switch until after the expiration of a predetermined period of time after it is opened under load.

The specific means illustrated in Fig. 1 to carry out the invention includes an electro-magnetic relay 60 having a movable or bridging member 62 which is adapted to bridge the contact members 64 which are arranged in series with the circuit 30 of the starting circuit controller. Said relay has an actuating winding 66 which is in series with the conductor 48 and thereby with the circuit of the electro-magnetic winding. Said relay is adapted to be energized as long as the switch 10 is closed, thereby to maintain its contact members disengaged and consequently to keep the circuit of the starting circuit controller open. When the switch 10 is opened by depressing the stopping button 30, the circuit 48 and consequently the relay 60 is de-energized and its contact members are free to be bridged thus to complete the circuit of the starting circuit controller.

Time-governed means as the dashpot 68 is associated with the relay, and is so arranged as to delay the movement of the bridging member 62 into circuit closing position for a suitable period of time after the switch 10 has been opened. This, the switch 10 can not be reclosed until the contacts 64 of the relay are bridged. The time-setting of the dashpot 68 is adapted to be long enough, ten seconds, more or less, to permit the contact members of the switch to cool and the arc gases to be dissipated.

In the modification illustrated in Fig. 2, the electro-magnetic relay 60 is replaced by a normally-closed thermal relay 70 which is here shown as identical with the construction 5 of the overload thermal relay above described.

The heater element 72 of the relay is included in series with the conductor 50 of the starting circuit controller. The contact members 74 of the relay are in series with the conductor 48 of the stopping circuit controller and the electro-magnet winding. With this arrangement, the heating element 72 is normally de-energized except for the time that the starting circuit controller is closed. The relay is so designed that the contact members 74 are not adapted to separate by the momentary current traversing the conductor 50, the adjustment being such that the contacts 74 will not open if the starting circuit controller is but momentarily closed, which is all that is necessary to effect the closing of the switch.

If, however, it is attempted to reclose the switch repeatedly and rapidly by successive operations of the starting push button, the accumulation of heat in the thermal member is adapted to be such that after two or three rapidly repeated operations, the thermal member expands and separates the contact members 74 thereby disabling the holding circuit 48 and preventing further reclosures of the switch until the thermal relay has dissipated its heat. Usually a switch can be opened rapidly a few times under its rated load without undue arcing but if the opening operations are continued, the accumulation of heat and arc gases thereafter results in destructive arcing. Thus, the arrangement shown in Fig. 2 will prevent rapidly repeated openings of the switch under load.

The broader idea of preventing the switch from being repeatedly opened rapidly under load is described and claimed in a copending application of George A. Burnham, Serial No. 367,340, filed May 31, 1929, and assigned to the assignee of this present application.

In Fig. 3, the arrangement is the same as in Fig. 1 except that a normally-open thermo-responsive relay 80 is substituted for the electro-magnetic relay 60. The electric resistance heating element 82 of said thermal relay is included in series with the closing circuit 48 and thus is maintained heated for 55 so long as the switch is closed. The thermo-responsive element 84 is maintained in flexed condition by the heated element 82 and thereby maintains the contact members 86 in separated condition. When the switch is opened, 60 however, either on overload, or by depressing the stopping button 30, the current flow in the closing circuit 48 is interrupted and the thermo-responsive element cools off and ultimately closes the contacts 86. Until these contacts are closed, however, no effect results

from the operation of the starting push button 28 and the period of time required for the contacts 80 to close is adapted to be sufficient to provide the desired time delay between successive opening and closing operations of the switch. 70

I claim:

1. The combination of an electric switch, electro-magnetic means for controlling the closing and opening of the switch, closing and opening circuits for said electromagnetic means, closing and opening circuit controllers associated with said respective circuits, and electrical means also associated with both and energized from one of said circuits arranged to disable the other circuit for a period of time sufficient to prevent the rapidly and indefinitely repeated opening of the switch. 75

2. The combination of an electric switch, electro-magnetic means for controlling the closing and opening of the switch, closing and opening circuits for said electro-magnetic means, closing and opening circuit controllers associated with said respective circuits, and electrical means operated by the current in one circuit to disable the other circuit for a period of time sufficient to prevent the rapidly repeated opening of the switch under load. 80

3. The combination of an electric switch, electro-magnetic means for controlling the closing and opening of the switch, closing and opening circuits for said electro-magnetic means, closing and opening circuit controllers associated with said respective circuits, separable contact members included in one of said circuits, and means actuated by the current in said other circuit to effect the control of said contact members and delay the successive openings of the switch. 85

4. The combination of an electric switch, electro-magnetic means for governing the closing and opening of the switch, closing and opening circuits for said electro-magnetic means, closing and opening circuit controllers associated with said respective circuits, separable contact members in one of said circuits, and time-delayed means actuated by the current in said other circuit to control said contact members and delay the reclosing of the switch after an opening thereof. 90

5. The combination of an electric switch, electro-magnetic means for governing the closing and opening of the switch, closing and opening circuits for said electro-magnetic means, closing and opening circuit controllers associated with said respective circuits, and thermally-actuated means controlled by the current in one of said circuits and having control of said other circuit to delay the reclosing of the switch following its opening. 100 105 110 115 120 125 130

1. The combination of an electric switch, electro-magnetic means for governing the closing and opening of the switch, closing and opening circuits for said electro-magnetic means, a closing and opening circuit contactor associated with said respective circuits, a thermal relay having normally closed contacts included in said closing and opening circuit, a heating element for separating said contacts, and an electric heating element for said thermal responsive element included in said opening circuit and arranged to effect the opening of said contacts when it is traversed by currents of rapidly repeated sequence in said starting circuit.
2. The combination of an electric switch, electro-magnetic means for governing the closing and opening of the switch, closing and opening circuits for said electro-magnetic means, a closing and opening circuit contactor associated with said respective circuits, a thermal relay having normally closed contacts included in said closing and opening circuit, a heating element for separating said contacts, and an electric heating element for said thermal responsive element included in said opening circuit and arranged to effect the opening of said contacts when it is traversed by currents of rapidly repeated sequence in said starting circuit.

7. The combination of an electric switch, opening and closing means therefor, closing and opening circuits for said aforesaid means, and means to provide a delayed period of time between reclosing operations of said switch including contact members arranged in one of said circuits, thermally-responsive operating means for said contact members, and heating means for said operating means heated by the current in said other circuit, said thermally-responsive operating means and said heating means constituting means to delay the operation of said contact members in response to the current in said other circuit.
